(57) **CLAIM**

The ornamental design for a lighting unit, as shown and described.

DESCRIPTION

The present application is related to and claims priority from prior U.S. application Ser. No. 12/247,145 filed on Oct. 7, 2008, the contents of which are incorporated herein by reference.

FIG. 1 is a front isometric view of a lighting unit, with the portion broken away to indicate indeterminate length;

FIG. 2 is a rear isometric view of the lighting unit;

FIG. 3 is a front view of the lighting unit;

FIG. 4 is a rear view of the lighting unit;

FIG. 5 is a top view of the lighting unit;

FIG. 6 is bottom view of the lighting unit;

FIG. 7 is a first end view of the lighting unit; and,

FIG. 8 is a second end view of the lighting unit.

The portions shown in broken lines are included to show environment and form no part of the claimed design.

1 Claim, 3 Drawing Sheets
